UNITED STATES PATENT OFFICE.

JACOB KITZ, OF NEUSCHLEUSSIG, NEAR LEIPSIC, GERMANY.

HANGING CIRCULAR SAWS.

SPECIFICATION forming part of Letters Patent No. 254,142, dated February 28, 1882.

Application filed December 18, 1880. (No model.) Patented in Germany October 8, 1880, in England November 30, 1880, in France December 15, 1880, and in Austria February 19, 1881.

To all whom it may concern:

Be it known that I, JACOB KITZ, of Neu-
schleussig, near Leipsic, in the Empire of Ger-
many, have invented a new and useful Improve-
ment in Circular Saws, (for which I made ap-
plication for Letters Patent in Germany on or
about the 6th day of October, 1880,) of which
the following is a specification.

The nature of my invention consists in ar-
ranging or securing the saw-blade to a ring
fitted over a hub securely attached to the axis,
said ring being arranged to turn around suitable
journals attached to the hub and secured
in any desired diagonal position by suitable
screws, whereby a groove of any desired width
may be cut into the wood according to the di-
agonal position of the ring and saw-blade to
the axis.

In the accompanying drawings, Figure 1
represents a front view of a circular saw em-
bodying my invention. Fig. 2 is a cross-section
of the same. Fig. 3 is a horizontal sec-
tion, showing the saw-blade square to the axis;
and Fig. 4 is a horizontal section, showing the
saw-blade placed diagonal to the axis.

Similar letters represent similar parts in all
the figures.

A is the axis, upon which a hub, B, is firmly
attached. This hub is provided with two pro-
jecting pins or journals, C C, opposite each
other.

D is a ring made in two parts, between
which the saw-blade E is firmly secured, and
provided with suitable holes, into which the
pins or journals C C of the hub are fitted, so
that said ring and saw-blade can easily turn
or swing on said pins or journals. Suitable
brasses, a, may be fitted into these holes to sur-

round the pins or journals. The two halves
forming the ring D are secured together by 40
suitable screws, b.

On one side of the ring D a lug or projec-
tion, F, is provided at right angles to the cen-
ter line of the journals C, through which a suit-
able screw, G, passes, screwing into the hub B, 45
by means of which the diagonal position of the
ring D and saw-blade E can be regulated.

J J are set-screws, arranged to act against
the pins or journals C C, or against their sur-
rounding brasses, to secure and fasten the ring 50
and saw-blade in the desired position.

Whenever the saw-blade is secured square
to the driving-axis, as shown in Fig. 3, the
groove cut into the wood will be of a width
corresponding with the thickness of the saw- 55
blade in the usual manner.

When a wider groove should be desired, the
saw-blade is secured, in the manner above de-
scribed, diagonal to the axis A, as shown in
Fig. 4, when the width of the groove to be cut 60
into the wood will depend upon the diagonal
position of the saw-blade in relation with the
axis A.

What I claim as my invention, and desire
to secure by Letters Patent, is— 65

In combination with a hub, B, firmly se-
cured to a driving-shaft, A, and provided with
projecting pins or journals C C, the ring D,
with saw-blade E, the screw G, and set-screws
J J, constructed and arranged to operate in 70
the manner and for the purpose substantially
as described.

JACOB KITZ.
